(57) **CLAIM**

The ornamental design for a shoulder strap for an infant carrier, as shown and described.

DESCRIPTION

FIG. 1 is a perspective view showing a shoulder strap for an infant carrier according to my new design;

FIG. 2 is a front elevational view thereof;

FIG. 3 is a side elevational view thereof, the other side being a mirror image; and,

FIG. 4 is a top plan view thereof.

1 Claim, 4 Drawing Sheets

FIG. 1

FIG. 2

FIG. 3

FIG. 4
